(57) **CLAIM**

The ornamental design for a walking-beam anchor chain tensioning apparatus, substantially as shown and described.

DESCRIPTION

FIG. 1 is a front elevational view of a walking-beam anchor chain tensioning apparatus according to the invention showing the new design, the rear view being identical;

FIG. 2 is a right side elevational view thereof;

FIG. 3 is a left side elevational view thereof;

FIG. 4 is a top plan view thereof; and,

FIG. 5 is a bottom plan view thereof.

Only a portion of the chain has been shown in the disclosure for ease of illustration.
